HYGINO DA TRINDADE DO CEU FARIA

By Harry C. Schneider
Attorney

UNITED STATES PATENT OFFICE.

HYGINO DA TRINDADE DO CEU FARIA, OF OAKLAND, CALIFORNIA.

FOLDING TABLE.

Application filed February 15, 1922. Serial No. 536,649.

To all whom it may concern:

Be it known that I, HYGINO DA TRINDADE DO CEU FARIA, a citizen of the Republic of Portugal, residing at Oakland, in the county 5 of Alameda and State of California, have invented certain new and useful Improvements in Folding Tables, of which the following is a specification.

My invention is an improved folding table 10 which is simple in construction and may be readily folded up compactly or unfolded.

Referring to the drawing forming a part of this specification:

Figure 1 is an elevation of my table unfolded and set up in position for use.

Figure 2 is an under side plan view of the table top unfolded and an elevation of the table standard folded and placed on the table top so that the top may be folded 20 around said standard.

Figure 3 is an elevation of the table completely folded.

Figure 4 is a top plan view of the table completely folded.

25 My table comprises a folding standard 1 and a folding top 2. The standard 1 comprises a rod 3, a body member 4 secured on said rod, legs 5, preferably three in number, pivoted to the lower end of said body member in brackets 6 secured to said member, a sleeve 7 slidable on rod 3, braces 8 pivoted at one end to said sleeve and at their other ends to said legs respectively, a head 9 secured on the upper end of the rod 3, a pivot member 10, table top supports 11 pivoted to said pivot member 10 in brackets 12 secured to said pivot member, equi-distant apart around said member, and braces 13 pivoted at their lower ends to the upper end of the 30 body member 4 and at their upper ends to the supports 11 respectively. The table top 2 comprises a center leaf 14 intermediate leaves 15-15 hinged by hinges 16-16 to the side edges respectively of said center leaf, 35 and outside leaves 17 hinged by hinges 18-18 hinged to the outer edges of said intermediate leaves respectively.

40 When the table is set up in position for use, the legs 5 are spread apart until limited by the engagement of their upper ends with the body 4 and by braces 8 extending from the lowermost position of sleeve 7 on rod 3; the supports 11 are unfolded into horizontal position and supported in such position by 45 the braces 13 and the pivot member 10 rest-

ing on top of the head 9; and the top 2 is unfolded flat and rests upon said supports 11.

To fold the table the top is first removed; the pivot member 10 is raised until the supports 11 and braces are folded parallel to rod 3; the sleeve 7 is raised on the rod 3 up to the body member 4 and the legs drawn inwardly by the braces 8, the folded standard 1 is then placed on the inside of the center table leaf 14 of the table top 2 with the legs 5 partly below the top as shown in Figure 2 and the leaves 15-15 folded on their hinges 16-16 and the leaves 17-17 folded on their hinges 18-18 completely 50 around the standard as shown in Figures 3 and 4.

Having described my invention, I claim:

1. A folding table including a standard and a table top, said standard comprising a 55 rod, a body secured on said rod, legs pivoted to said body, a sleeve slidable on said rod, braces pivoted to said slide and to said legs respectively, a head secured on the upper end of said rod, a pivot member adapted to rest on said head, supports pivoted to said pivot member, and braces pivoted to said body and to said supports respectively.

2. A folding table including a standard, said standard comprising a rod, a body secured on said rod, legs pivoted to said body, a sleeve slidable on said rod below the pivot point of the legs, braces pivoted to said slide and to said legs respectively, a head fixedly secured on the upper end of said rod, a pivot member adapted to rest on said head when the table is unfolded but detached therefrom when the table is folded, supports pivoted to said pivot member and braces pivoted to said body and to said supports respectively. 65

3. A folding table including a fixed rod, a body member and a head member both rigidly secured to said rod, a pivot member adapted to rest on the upper end of the head member when the table is unfolded, supports pivoted to the pivot member and braces pivoted to the body member and to the supports intermediate of their lengths whereby the pivot member may be raised above the head member by pressing down on the outer ends 70 of the support members and means for supporting the body member.

In testimony whereof I affix my signature.

HYGINO DA TRINDADE DO CEU FARIA.
